Inventor

ALFRED W. LAWSON

By Watson E. Coleman

Attorney

UNITED STATES PATENT OFFICE.

ALFRED W. LAWSON, OF GREEN BAY, WISCONSIN.

PEDAL.

1,287,356.

Specification of Letters Patent. Patented Dec. 10, 1918.

Application filed January 5, 1918. Serial No. 210,580.

To all whom it may concern:

Be it known that I, ALFRED W. LAWSON, a citizen of the United States, residing at Green Bay, in the county of Brown and State of Wisconsin, have invented certain new and useful Improvements in Pedals, of which the following is a specification, reference being had to the accompanying drawings.

10 This invention relates to certain improvements in pedals and has relation more particularly to a device of this general character especially designed and adapted for use in connection with the rudder bar of an aeroplane or the like, and it is an object of the invention to provide a novel and improved device of this general character which may be readily engaged and disengaged from the bar.

15 It is also an object of the invention to provide a pedal embodying an electrical heating unit which when the pedal is applied to the rudder bar is properly interposed within an electrical current so that the foot of an aviator or other person is kept warm irrespective of the altitude which the aeroplane may reach.

An additional object of the invention is to provide a novel and improved pedal having 30 suitably arranged therein an electrical heating coil having its terminals connected with a pair of securing plates together with a rudder bar provided with sockets to receive said plates, said sockets being in connection 35 with a source of electrical energy so that upon insertion of the plates or plugs within the sockets a circuit will be closed resulting in the desired radiation of heat from the coil carried by the pedal.

40 A still further object of the invention is to provide a novel and improved construction embodying a pedal provided with a pair of arms or plugs insertible within sockets suitably carried by a rudder bar or the like 45 together with means carried by the rudder bar and coacting with the plates or plugs for locking the pedal to the rudder bar.

The invention consists in the details of construction and in the combination and arrangement of the several parts of my improved pedal whereby certain important advantages are attained and the device rendered simpler, less expensive and otherwise more convenient and advantageous for use, 55 as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in top plan with portions broken away illustrating an embodiment of my invention;

Fig. 2 is an enlarged fragmentary view 65 in elevation of an end portion of the rudder bar as herein disclosed;

Fig. 3 is a sectional view taken substantially on the line 3—3 of Fig. 2;

Fig. 4 is a longitudinal sectional view 70 taken through a pedal as herein set forth;

Fig. 5 is a transverse sectional view taken substantially on the line 5—5 of Fig. 4; and

Fig. 6 is a view in perspective of a pedal 75 as herein included.

As disclosed in the accompanying drawings R denotes a rudder bar adapted to be pivotally engaged as at 2 at substantially its longitudinal center for swinging movement. As is particularly illustrated in Fig. 80 3, it is to be observed that the bar R comprises two superimposed strips or layers 3 of insulating material and which are maintained in assembled relation through the medium of the rivets 4 or other fastening 85 means. Coacting with the opposite end portions of the strips 3 are the tips or caps 5 maintained in applied position by the bolts 6 or the like which also serve as an additional medium for maintaining the strips or 90 layers 3 in assembled relation. The caps or tips 5 are provided with the perforate ears 7 with which the flexible members leading to the rudder of an aeroplane are adapted to be connected.

Each end portion of the bar R has interposed between the strips or layers 3 thereof a pair of metallic sockets 8 maintained in applied position in any desired manner, but preferably through the medium of the 100 screws 9 as is particularly illustrated in Fig. 2 of the accompanying drawings. The inner sockets of both pairs of sockets 8 are electrically connected by the conductor *a* while the outer sockets are in connection with a suitable source of electrical energy through the medium of the conductors *b*. The conductors *a* and *b* may be arranged in a manner which best meets with the requirements of practice, but as is particu- 110

- larly illustrated in Figs. 1 and 3, said conductors *a* and *b* being arranged within the channels or passage ways 10 formed in the inner face of one or both of the strips or layers 3 of the bar R.
- 5 Each of the pedals P is of slipper formation and includes an outer metallic sole or plate 11 to which are secured to the ball portion thereof a pair of plates or plugs 14 and one of said plugs is insulated as at 15 from the plate 11. The plates or plugs 14 are in predetermined transverse spaced relation and the extended or free end portions thereof are adapted to be snugly received 15 within a pair of sockets 8. Imposed upon the sole or plate 11 are the laminations 16 of asbestos or similar material and interposed between certain of said laminations 16 is a heating coil 17 having its terminals 20 suitably connected with the plates 14 so that when a pair of pedals are operatively engaged with the opposite end portions of the bar R an electrical circuit will be closed resulting in the requisite radiation of heat 25 from each of the coils 17 so that the foot of the aviator or other person engaged with the pedal P will be maintained warm irrespective of the altitude the aeroplane may reach.
- 30 Each of the arms or plugs 14 is provided at a predetermined point intermediate its length with an opening 18 adapted to receive the suitable openings 19 produced in the coacting socket 8. The upper opening 35 19 is in register with a recess or pocket 20 formed in the inner face of the upper layer or strip 3 while the lower opening 19 is in communication with the opening 21 extending through the lower strip or layer 3.
- 40 The opening 21 is provided with a metallic lining 22.
- 45 23 denotes a pin extending upwardly through the lower strip or layer 3 of the rod R and is of a length to extend through the registering openings 18 and 19 and into the recess or pocket 20 so that the arm or plug 14 will be effectively locked to the rudder bar R. The pin 23 is provided with the enlarged channeled head 24 arranged below 50 the rudder bar R and which serves to limit the upward movement of the pin 23. Straddling the grooved head 24 is a yoke 25 of a key 26. The key 26 is substantially L-shape in form and has its stem extending upwardly 55 and pivotally engaged as at 27 between the spaced ears 28 extending forwardly from the bar R. The upper end portion of the arm of the key 26 is provided with a button 29 or the like to facilitate imparting to the key 60 26 the requisite rocking movement to withdraw the pin 23 from operative engagement with an arm or plug 14 so that the pedal P may be readily removed.

The pin 23 is normally maintained at the 65 limit of its upward or inward movement

through the medium of the retractile member herein disclosed as a coil spring suitably anchored at one end to the key 26 below its pivotal mounting 27 and at its opposite end to a plate 31 suitably carried by the lower 70 face of the rod or bar R. As is particularly illustrated in Fig. 3, the pin 23 is also loosely directed through the plate 31.

From the foregoing description, it is thought to be obvious that a pedal constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with the rudder bar of an aeroplane or other similar structure, a pedal engaged therewith, and heat radiating means carried by the pedal.
2. The combination with an operating member, a pedal connected thereto, and heat 95 radiating means carried by the pedal.
3. The combination with an operating member, a pedal connected thereto, and heat radiating means carried by the pedal, said heat radiating means being under control 100 of the connection between the pedal and the member.
4. In combination with an operating member, sockets carried by said member and adapted for connection with a source of electrical energy, a pedal, plugs carried by the pedal and insertible within the sockets of the member, and a heating coil carried by the pedal and having its extremities connected to the plugs.
5. In combination with a member, sockets carried by said member and adapted for connection with a source of electrical energy, a pedal, plugs carried by the pedal and insertible within the sockets of the member, a heating coil having its extremities connected to the plugs, and means coacting with said member and the plugs for holding the plugs normally against withdrawal from within the sockets.
6. In combination with the rudder bar of an aeroplane or other similar structure, pedals carried by the opposite end portions of the bar, and electrically operated heating means carried by the pedals and connected 125 in series.
7. In combination with the rudder bar of an aeroplane or other similar structure, pedals carried by the opposite end portions of the bar, and electrically operated heating 130

means carried by the pedals and connected in series, each of said pedals being independently secured to the bar.

8. In combination with the rudder bar of an aeroplane or other similar structure, a pedal, an electric heater carried by the pedal, and coacting means carried by the pedal and the bar for mounting the pedal upon the bar and for energizing the electric heater when the pedal is in position upon the bar.

9. In combination with an operating member, sockets carried by said member and adapted for connection with a source of elec-

trical energy, a pedal, plugs carried by the pedal and insertible within the sockets of the member, and a heating coil carried by the pedal and having its extremities connected to the plugs, said plugs and sockets coacting to secure the pedal to the operating member.

In testimony whereof I hereunto affix my signature in the presence of two witnesses.

ALFRED W. LAWSON.
